CLAIM

The ornamental design for a container for a torte or the like, as shown and described.

DESCRIPTION

FIG. 1 is a perspective view of a container for a torte or the like showing my new design;

FIG. 2 is a left-side elevational view thereof (a right side elevation being a mirror image thereof);

FIG. 3 is a bottom plan view thereof; and

FIG. 4 is a rear elevational view thereof.

FIG. 1FIG. 2FIG. 3FIG. 4
